UNITED STATES PATENT OFFICE.

OLIVER S. SLEEPER, OF BUFFALO, NEW YORK, ASSIGNOR TO BUFFALO FOUNDRY & MACHINE COMPANY, OF BUFFALO, NEW YORK, A CORPORATION OF NEW YORK.

METHOD OF DRYING LIQUID MATERIALS.

1,178,108.

Specification of Letters Patent.

Patented Apr. 4, 1916.

Application filed October 3, 1912. Serial No. 723,698.

To all whom it may concern:

Be it known that I, OLIVER S. SLEEPER, a citizen of the United States, residing at Buffalo, in the county of Erie and State of New York, have invented new and useful Improvements in Methods of Drying Liquid Materials, of which the following is a specification.

This invention relates to a method of drying or desiccating liquid materials so as to reduce them to a flaked granular or powdered condition, this invention being employed for instance in producing dry or powdered chestnut or other wood extracts, also dry or powdered glue, milk drugs, food products, &c., by removing the water or moisture from the solid ingredients in these materials.

One of the objects of this invention is to apply the material to be dried more uniformly upon the surface whereon the same are dried and to increase the amount of the material deposited upon this surface beyond that possible in machines of this character as heretofore constructed and thereby increase the output of the machine and reduce the cost of production accordingly.

Another object of this invention is to so construct the machine that the liquid material to be dried is circulated in the most direct manner and with the employment of a minimum length of conduits and angular connections so that the fullest efficiency is obtained by the means whereby the liquid to be dried is circulated in the machine.

A further object of this invention is to supply the liquid material to be dried under pressure while confined against the drying surface so that the same is forced or pressed against the surface upon which the same is dried and this surface is caused to take up and dry a larger amount of this material than when this drying surface is only supplied by a stream of the material without pressure or when said surface only dips into a bath or stream of the material to be dried.

In the accompanying drawings consisting of 3 sheets: Figure 1 is a vertical longitudinal section of a drying apparatus which is constructed in accordance with my invention and whereby my improved process for drying liquid material may be practised, the section being taken in line 1—1, Fig. 2, but on a reduced scale. Fig. 2 is a vertical transverse section, on an enlarged scale, of

the machine taken in line 2—2, Fig. 1. Fig. 3 is a horizontal section, on a reduced scale, taken in line 3—3, Fig. 2. Fig. 4 is a vertical transverse section of the pump taken in line 4—4, Fig. 1, whereby the liquid material to be dried is circulated in the machine.

Similar characters of reference indicate corresponding parts throughout the several views.

In its general organization the machine which is shown in the drawings and which embodies my invention and permits of practising my improved process of drying or desiccating liquids comprises a vacuum or drying chamber 1 and a drying or heating drum 2 which rotates about a horizontal axis within the drying chamber. The vacuum chamber is preferably formed by an inclosing casing or housing comprising a body 3¹ constituting the longitudinal sides, top and bottom of the casing and two heads 3, 4 which are detachably secured to opposite ends of the body. The lower part of the casing is constructed to form a catch basin or reservoir 5 for the liquid to be dried and 70 a residuum chamber, spout or delivery passage 6 which is adapted to receive the dried product of the liquid. The reservoir and discharge passages 5, 6 are arranged lengthwise side by side and separated by an upright wall or partition 7, as shown in Fig. 2. At the top of the casing the same is provided with a vapor outlet 8 which is adapted 75 to be connected with an exhausting device of any suitable character for removing the vapors from the interior of the drying chamber, this exhaust device consisting for instance of a vacuum pump or condenser or both.

The drying drum comprises a horizontal cylindrical body 9 and two heads 10, 11 secured to opposite ends of the drum body and provided with hollow trunnions 12, 13 which are journaled in bearings 14, 15 on the heads of the drying chamber. Rotation 100 of the drum, in the direction of the arrow 16 indicated in Fig. 2, may be effected by any suitable means so that the lower part or side of the drum moves from the discharge passage to the reservoir. The means shown in the drawings for rotating the drum comprises a driven gear wheel 17 which is secured to the outer end of the trunnion 13 and which is operatively connected by intermediate gearing with a pulley 18 which re- 110

ceives a driving belt. The heating of the drum may be effected in various ways, those shown in the drawings being suitable and comprising a stationary steam supply pipe 5 19 entering the hollow trunnion 13 and a stationary delivery pipe 20 for carrying the water of condensation arranged in the other trunnion 12 and connected with a drain scoop 21 arranged adjacent to the bore of 10 the drum.

The liquid material containing solid matter to be dried is applied to the drum on the underside of the same and then carried over the top thereof during which movement the 15 moisture in the solid elements of the material is eliminated by the heat of the drum while the solid ingredients cling to the periphery of the drum. The liquid to be dried is delivered to the drum by means 20 of a feed pan arranged below the drum and comprising a bottom 22, a rear longitudinal flange or wall 23 rising from the rear longitudinal edge of the bottom and engaging with the periphery of the drum, two trans- 25 verse side or end walls 24, 24 arranged at opposite ends of the bottom and also projecting upwardly therefrom into engagement with the periphery of the drum, and a vertically movable gate, valve or front wall 30 25 which is adjustably connected with the relatively fixed parts of the pan and adapted to have its upper edge arranged separate from the periphery of the drum and thus form an outlet passage for the pan through 35 30 which the excess liquid which is not taken up by the surface of the drum drops from the pan into the reservoir of the casing. The preferred means for adjusting the gate or valve of the pan which are shown in the 40 drawings comprise a plurality of vertical slots 26 formed in the lower edge of the gate, and a plurality of clamping bolts 27 each passing through one of the slots 26 and connecting the gate with a depending flange 45 40 on the front edge of the bottom of the pan.

The delivery pan is of a length substantially equal to that of the drum and is mounted on the rear ends of a plurality of 50 55 vertically swinging rock arms 29 which latter are secured at their front ends to a horizontal rock shaft 30 arranged lengthwise in the drying chamber below the drum and journaled at its opposite ends in stuffing boxes 31 on the heads of the drying chamber. Upon turning this shaft and its arms in one direction the pan is swung downwardly away from the drum into a position in which the same may be thoroughly 60 65 cleaned and maintained in a sanitary condition, while upon turning this shaft and its arms in the opposite direction the pan will be swung upwardly into engagement with the drum. This movement of the rock shaft and the parts associated therewith is

preferably effected by means of a hand lever 32 secured to one end of this shaft outside of the casing and held in place by means of a clamping device 33 while the pan is in engagement with the drum.

Below the pan is arranged a horizontal longitudinal liquid delivery manifold 34 which is connected on its upper side with the bottom of the pan by means of a plurality of upright nozzles or nipples 35 70 75 whereby the liquid is delivered from the manifold into the pan at different points in the length thereof. This manifold is preferably mounted on the free or rear parts of the rock arms 29 by passing the same 80 through openings 36 formed in these arms, as shown in Fig. 2.

37 represents a liquid delivery pipe or conduit arranged vertically below the drum and extending through the bottom of the 85 reservoir. At its upper end this delivery pipe is connected with the manifold in such manner that the pan and manifold are free to be raised and lowered for cleaning, inspecting and repairing without disturbing 90 the liquid delivery connections between these parts. The preferred means for this purpose which are shown in the drawings consist in providing the upper end of the delivery pipe 37 with a fixed hollow coupling head 38 through which the rock shaft 30 passes, and a movable hollow coupling head 39 which receives the rock shaft and is connected by a hollow arm or branch pipe 40 with the manifold. The fixed and movable coupling heads engage with each other by means of a rotatable joint 41 which is concentric with the axis of the rock shaft, thereby maintaining the liquid connections 100 between the delivery pipe and the manifold 105 in the various positions which the latter assumes upon raising and lowering the same together with the pan.

For the purpose of steadyng and holding the upper end of the delivery pipe in 110 position within the vacuum chamber this end of this pipe is connected with the front wall or adjacent part of the casing by means of a brace which is preferably adjustable and constructed of two horizontal rods 42, 43 which have their extremities connected respectively with the front side of the delivery pipe at the upper end thereof and with the inner side of the front wall on the casing, and a turn buckle 44 which is connected by means of right and left hand screw threads with the opposing ends of the rods 42, 43, as shown in Figs. 2 and 3.

45 represents a liquid supply pipe whereby the liquid to be dried is withdrawn from the reservoir and which extends downwardly from the bottom of this reservoir adjacent to the liquid delivery pipe 37 connecting with the delivery pan. In order to 125 deliver the liquid from the reservoir to the 130

pan as directly as possible and with a minimum number of turns in the course of this liquid a rotary pump is employed the casing 46 of which has its inlet 47 and its outlet 48 arranged at the top thereof and connected with the lower ends of the supply and delivery pipes 45, 37, respectively, so that the liquid from the reservoir can descend directly into the cylinder or casing of the pump without making any turns during this course and then be ejected or forced by the wings 49 of the piston 50 in the casing or cylinder of the pump upwardly through the delivery pipe and to the pan with a minimum deflection in the course of the liquid before reaching the drum. By this means the liquid to be dried is circulated in the machine with a minimum expenditure of power, the machine can be produced at less cost, less piping needs attention for keeping the machine clean, and the apparatus is also more compact as a whole.

During the operation of the machine the liquid to be dried passes from the reservoir downwardly through the supply pipe 45 into the pump casing thence upwardly through the delivery pipe 37 and into the manifold, thence into the delivery pan where a quantity of the same adheres to the outer surface of the drum in the form of a thin film while the surplus flows through the outlet of the pan at the front end thereof and drops back again into the reservoir to be again circulated in the manner described. The film of liquid adhering to the exterior of the drum as it passes over the pan is dried by the heat within the drum as the liquid passes upwardly on the front and downwardly on the rear side of the latter. Before the dried material on the drum reaches the liquid feeding position this material is removed from the periphery of the drum by a scraper, knife or doctor 51 which projects upwardly from a position adjacent to the partition 7 and directs the material into the product receiving chamber or delivery passage, thereby clearing the drum so that the same is ready to receive another coat of undried liquid. The outlet of the delivery passage may be connected in any suitable manner with a receptacle into which the dried material is delivered, it being understood that this receptacle is of the usual construction and its connection with the discharge passage is of such a character as to permit of maintaining the vacuum within the drying chamber while the machine is in operation. In this machine the width of the pan between its front and rear edges is materially reduced

so as to obtain the maximum amount of active heating surface of the drum, thereby increasing the drying effect of the same and the output of the machine accordingly. By means of the gate or valve 25 the overflow outlet of the pan may be adjusted or regulated as to size or capacity in order to regulate the pressure in accordance with the requirements of the densities of different materials which may be dried and also to obtain the best results under the different conditions under which the machine may be operated.

In operating the machine the liquid to be dried is delivered against the heating drum under a pressure by the pump and while the liquid is confined against the drum which pressure varies according to the character of the material being dried, thereby increasing the amount of deposit of solid materials against the drum and expediting the drying operation in the same measure. The pump is operated to produce a pressure upon the liquid or extract while the same is presented by the pan to the drum which enables this machine to dry a larger volume of liquid material within a given time than has been possible heretofore.

In order to insure a uniform deposit of the film of liquid on the surface of the drum after the latter has been coated by the pan a spreading device is provided which preferably consists of a blade or bar 52 arranged adjacent to the periphery of the drum immediately in front of the pan and mounted by means of arms 53 on the rock shaft 30.

I claim as my invention:

The herein-described method of desiccating liquids which consists in presenting the liquid to be dried under pressure and in the form of a continuously flowing stream to the underside of a heated circular drum which latter moves constantly and presents new surfaces to said stream of liquid into which its successive parts dip and pick up a thin film of this liquid by adhesion, said liquid being supplied to said drum in excess of the picking up capacity of the drum and the excess liquid not picked up by the drum being dropped from the drum, and the liquid picked up by said drum being dried thereon and removed continuously from the surface thereof preparatory to receiving a new coat of liquid.

Witness my hand this 1st day of October, 1912.

OLIVER S. SLEEPER.
